UNITED STATES PATENT OFFICE.

GEORGE NEWTON CLARK, OF DRY RIDGE, KENTUCKY.

BUCKLE.

SPECIFICATION forming part of Letters Patent No. 604,912, dated May 31, 1898.

Application filed May 12, 1897. Serial No. 636,192. (No model.)

To all whom it may concern:

Be it known that I, GEORGE NEWTON CLARK, a citizen of the United States, residing at Dry Ridge, in the county of Grant and 5 State of Kentucky, have invented a new and useful Buckle, of which the following is a specification.

This invention relates to that class of harness-buckles which operate without the provision of a tongue and the necessity of piercing the strap for the positive engagement therewith of the tongue; and the purpose of the improvement is to direct the locking wedge or slide in its movements, prevent disengagement of the wedge from the box, and to secure a neat and effective buckle which will be devoid of projecting parts and operate in a satisfactory manner.

The improvement consists, essentially, of a box-frame adapted to have a strap secured to one end thereof and having its top outwardly and rearwardly inclined and its sides parallel, outwardly convergent, and longitudinally bulged, forming inner longitudinal 25 guideways adjacent to and parallel with the bottom of the box, the inner ends of the guideways being contracted and a wedge having a loop at its rear end and slideable within the box through its rear end and having lateral 30 extensions operating in the aforesaid guideways and adapted to engage with the inner contracted ends of the guideways and prevent outward displacement of the wedge.

The invention also consists of the novel features and details of construction which hereinafter will be more particularly set forth, illustrated, and finally claimed.

In the drawings, Figure 1 is a perspective view of a buckle constructed in accordance 40 with this invention, showing it as it will appear when connecting the ends of two straps. Fig. 2 is a longitudinal section. Fig. 3 is a transverse section. Fig. 4 is a plan view of the wedge or locking-slide. Fig. 5 is a detail 45 view in perspective of the buckle-frame, parts of the box being broken away to show the contracted portion of the side guideways to engage with the lateral projections of the wedge and prevent the disengagement there- 50 of from the buckle.

Corresponding and like parts are referred to in the following description and indicated

in the several views of the drawings by the same reference characters.

The buckle-frame comprises a box 1 and an end extension 2, to which a strap 3 is secured in any of the usual ways either by being riveted thereto or passed through a loop and having its end portion folded and fastened. The box 1 has its space tapering or contracted 55 slightly at its outer end and is formed at its sides with guideways 4, in which operate lateral extensions 5 of the wedge or locking-slide 6. The guideways are closed and conceal the lateral extensions 5 and are formed 60 by bulging the sides of the box, so that a minimum amount of material is employed in the construction of the buckle and the latter made as light as possible consistent with durability and efficiency of service. The inner 65 ends of the guideways 4 are contracted, so as to engage with the lateral extensions 5 and prevent the wedge or locking-slide 6 from being withdrawn from the box when moved to a position for loosening the strap 7 or admitting of the said strap being placed in position within the box prior to being secured. 70

The wedge 6 fits snugly within the box 1, so as to prevent lateral movement, and is of a thickness to leave a space between its outer 80 side and the outer wall of the box for the reception of the strap 7, which latter is bound by a wedging action between the outer wall of the box 1 and the locking-slide 6 when the latter is forced within the box. The lateral 85 extensions 5 are an integral part of the wedge and are located at its smaller end to admit of the wedge being withdrawn from the box nearly its entire length. A loop 8 is formed at the outer end of the wedge to receive the 90 loose end of the strap 7 after the latter has been secured. The lateral extensions 5 are at all times housed and protected by the guideways 4 and do not present projecting parts to engage with the horse's mane or tail, 95 parts of the harness, or the hand and result in injury thereto, and being concealed do not detract from the appearance of the buckle.

As clearly indicated, the sides of the box are parallel and outwardly convergent, and 100 its top inclines to the plane of the bottom outwardly and rearwardly. The guideways 4 are adjacent to the bottom of the box and parallel therewith. The lateral extensions 5

and guideways 4 are of such relative proportion as to admit of the wedge turning on the said extensions, which is necessary to admit of the strap 7 being properly positioned with reference to the wedge and box. The wedge cannot escape from the box by a forward movement, as the end portions of the loop 8 will engage with the inner or rear end of the sides of the box, and its inner or rearward movement is limited by the extensions 5 engaging with the contracted ends of the guideways 4. It will thus be seen that the wedge cannot be lost or accidentally misplaced and is at all times in position for service.

Having thus described the invention, what is claimed as new is—

A buckle comprising a box having its bottom extended at one end for connection therewith of a strap, and having its sides parallel and outwardly convergent and longitudinally bulged, forming inner guideways adjacent to

and parallel with the plane of the bottom, the inner ends of the guideways being contracted, and having its top outwardly and rearwardly inclined to the plane of the bottom, and a wedge of corresponding width to the box and slideable therein through its inner or rear end and having a loop at its inner or rear end and lateral extensions at its smaller or front end which operate in the aforesaid guideways and hold the wedge against the said bottom, and which limit the rearward movement of the wedge by engaging with the inner contracted ends of the guideways, substantially as and for the purpose specified.

In testimony that I claim the foregoing as my own I have hereto affixed my signature in the presence of two witnesses.

GEORGE NEWTON CLARK.
